J. W. ESTES & W. H. BUCKLEY.
Permutation Padlock.

No. 228,619.

Patented June 8, 1880.

UNITED STATES PATENT OFFICE.

JOHN W. ESTES, OF HARRISON, ARKANSAS, AND WILLIAM H. BUCKLEY,
OF SPRINGFIELD, MISSOURI.

PERMUTATION-PADLOCK.

SPECIFICATION forming part of Letters Patent No. 228,619, dated June 8, 1880.

Application filed February 14, 1880.

To all whom it may concern:

Be it known that we, JOHN W. ESTES, of Harrison, county of Boone, State of Arkansas, and WILLIAM H. BUCKLEY, of Springfield, in the county of Green and State of Missouri, have invented certain new and useful Improvements in Permutation-Padlocks; and we do hereby declare that the following is a full, clear, and exact description of the invention, which will enable others skilled in the art to which it appertains to make and use the same, reference being had to the accompanying drawings, which form a part of this specification, and in which—

Figure 1 is a front elevation of our improved permutation-padlock. Fig. 2 is a view with the face-plate of the case or lock removed, exposing the internal mechanism. Fig. 3 is a vertical section taken transversely through the lock. Fig. 4 is a reversed view of the face-plate detached from the lock-case. Fig. 5 is a detailed view of the bolt, and Fig. 6 is a view of the several tumblers in side elevation.

Corresponding parts in the several figures are denoted by like letters.

This invention relates to certain improvements in permutation or combination padlocks; and it consists in the detailed construction and combination of the parts, substantially as hereinafter more fully set forth.

In the drawings, A refers to the lock case or shell, with one side (the face-plate A') cast or made separate therefrom, which plate or side is formed with a stud or projection, a, to fit into a socket or notch, a', in the lower part of the case, and with a right-angled plate or extension, a², perforated and fitting down upon the upper end of the case A. The hasp-staple passes through the perforation of the right-angled extension a² of the face-plate, by which, with the insertion of the projection a of said plate into its socket in the case, the plate is detachably or removably locked in place. Around the inner surface of the curved portion of the case may be cast or formed a flange, b, to enable the locking mechanism to be properly held in position.

B is the bolt, which is pivoted upon a stud, c, cast with or attached to the case A. The forward end of the bolt B, owing to its being

arranged in such close proximity to the top of the lock-case to economize in space, is reduced, as seen in Fig. 2, by which a tongue, b', is formed thereon, for the lower end of one of the arms of the hasp-staple C to rest on. 55 This end of the bolt is also provided with a lip or projection, b², which, when the tongue b' of the bolt is pressed down by the lower end of arm of staple, catches into a notch, c', in said arm of staple, locking the latter in 60 place when the other end of bolt has been elevated into contact with that arm of the staple resting upon said end of the bolt. A spring, d, bearing against the upper end of the lock-case and attached to the bolt, holds the latter 65 in the slots in its tumblers when the bolt is unlocked. The bolt B is curved or bent into a hook shape, as shown at b³, its beak entering the peripheral slots of its tumblers, as clearly represented in Fig. 2.

D D' D² D³ are the tumblers or disks, having each a peripheral slot, d d² d³ d⁴, and adjusted each upon a step or shoulder of a stepped conical shaft or spindle, e, cast with or otherwise attached to the case A. This 75 shaft is tubular, and receives a supplemental shaft or stem, f, of the disk or tumbler D. The same tumbler is provided with a pin, g, passing through slots in the other tumblers. These slots (designated by the letters h h' h²) 80 are segmental in form, and no two of the same length, by which it will be observed that, as the tumbler D is turned by manipulating the dial on the face-plate of the lock, each of the slotted tumblers will be moved separately a 85 limited distance independently of the others, and thus permit the confusing or moving of their peripheral slots out of line with each other when the hooked end of the bolt is elevated out of said slots, which result is produced by pressing downwardly upon the hasp-staple, which will cause the locking of the bolt and staple.

Upon the face-plate of the lock is a stationary ring or circle, E, with a series of numbers, 95 or figures, or letters, or characters, which ring or circle is raised from the surface of the plate, to provide an annular recess for the reception of the dial plate or disk F, also provided with a circle of figures or numbers, &c.

The dial-plate F is supplied with the key-hole or socket *i* upon its external surface, and upon its rear side with a hub, *i'*, having an angular socket or barrel and a circumferential groove in its exterior surface.

j is a plate detachably or removably adjusted to the same side of face-plate, and having prongs or arms *j' j''*, the inner or opposite edges of which enter the circumferential groove of the hub *i'*, to hold the latter in position, so as to permit of its being rotated. The hub *i'* receives an angular stud, *k*, projecting from the tumbler D, and forms the connection between the dial-plate and tumblers.

15 By causing both ends of the detachable hasp to impinge upon the bolt in the manner described, when the lock is locked, it is impossible to pick this by forcing the bolt, inasmuch as it (the bolt) is supported at both ends by the 20 hasp staples or tenons, which effectually prevent the bolt from being turned upon its pivot except by the regular process of unlocking.

Having thus fully described our invention, we claim and desire to secure by Letters Patent of the United States—

1. In a permutation-padlock, the combination, with the inclosing-case, of the pivoted bolt having one end provided with a tongue and lip or catch and the other end formed 30 into a hook, the detachable notched hasp-staple with both ends resting upon the bolt when locked, and the peripherically-slotted tumblers, substantially as and for the purpose set forth.

35 2. In a permutation-padlock, the combination, with the pivoted bolt and its locking mechanism, of the detachable hasp-staple, both of

whose ends rest upon the bolt, and are thus secured in a locked position, substantially as set forth.

3. In a permutation pad or other lock, the combination, with the inclosing-case having a notch or socket in one end, and in its top end one or more apertures, of the front or face plate having a projection at its lower or 45 one end and a right-angled perforated plate at its upper end, and the detachable hasp-staple, substantially as and for the purpose specified.

4. The combination of the inclosing-case, 50 with its face-plate provided with a dial-plate and registering circle or ring, a series of tumblers having segmental slots of unequal length, and also peripherical slots, and one tumbler provided with a pin entering the said segmental slots of the other tumblers, a pivoted bolt having one end provided with a tongue and lip and the other end with a hook and a detachable hasp-staple, whose ends penetrate the lock-case and rest upon the bolt, substantially 55 as and for the purpose set forth.

In testimony that we claim the foregoing as our own we have hereto affixed our signatures in presence of two witnesses.

JOHN W. ESTES.
WILLIAM H. BUCKLEY.

Witnesses as to signature of John W. Estes:

R. S. ARMITAGE,
J. M. DOUBLEDAY.

Witnesses as to signature of William H. Buckley:

T. H. B. LAWRENCE,
GEO. COMSTOCK.
